UNITED STATES PATENT OFFICE.

RUSSELL R. JOHNSTONE, OF WAUWATOSA, WISCONSIN.

DESIGN FOR AN ADVERTISING-SIGN.

55,471.

Specification for Design.

Patented June 15, 1920.

Application filed March 13, 1920. Serial No. 365,669. Term of patent 7 years.

To all whom it may concern:

Be it known that I, RUSSELL R. JOHNSTONE, a citizen of the United States, residing at Wauwatosa, county of Milwaukee, and State of Wisconsin, have invented a new, original, and ornamental Design for Advertising-Signs, of which the following is a specification, reference being had to the accompanying drawing, forming part thereof.

Fig. 2 is a side elevation thereof.

I claim:

The ornamental design for an advertising sign, as shown.

RUSSELL R. JOHNSTONE.
